CARRIAGES & WAGONS.
Children's Carriages

EXAMINER'S ROOM

NO. 11,148

April 8, 1879

UNITED STATES PATENT OFFICE.

WILLIAM B. WHITNEY, OF LEOMINSTER, MASSACHUSETTS.

DESIGN FOR CHILD'S-CARRIAGE BODY.

Specification forming part of Design No. **11,148**, dated April 8, 1879; application filed March 7, 1879.
[Term of patent 3½ years.]

To all whom it may concern:

Be it known that I, WILLIAM B. WHITNEY, of Leominster, in the county of Worcester and State of Massachusetts, have originated and designed a Child's-Carriage Body, of which the following is a full, clear, and exact description, reference being had to the accompanying printed illustration, making part of this specification.

The carriage-body has an upper rail, *a*, which is concaved at 2 near the center of the body, and from 2 the said rail is curved, and rises therefrom toward the extreme front end, 3, and rear end, 4, of the body.

About the lower rounded end of the body is a bottom rail, *b*, which is curved at 1 1, to be connected with the springs which support the body, thereby making the body appear deeper directly below the concaved portion 2.

At the side of the body is a panel, *c*, (shown as of shield shape,) it connecting the top and bottom rails, and at the front of the body is a front panel, *d*.

Between the upper and lower rails, *a b*, the outer face of the body is composed of woven-cane panels *e f*. These face panels, *e f*, of the body are continuous without angles from the side panels, *c*, to the median lines at the front and back of the body, so as to form a rounded front and back extending the depth of the body.

The whole upper portion of the body is surrounded by a plated or other top rail, *g*, which, supported by posts *h*, forms a tasteful trimming for the top of the body.

It is obvious the shape of the small panels *c d* might be modified without departing from the essence of my design for the body.

The shield-shaped panel *c* is filled in with

diagonal strips of cane 5, and the front panel, *d*, with diagonal strips 6, running in opposite directions.

I claim—

1. A design for a carriage-body, consisting of the elevated ends 3 and 4, concaved central portion, 2, and rounded face panels, *e f*, forming ends without angles, as shown.
2. A design for a carriage-body, it consisting of a body rounded at its front and rear ends, and having woven cane panels, upper and bottom rails, *a b*, and a side panel between the said rails, as shown and described.
3. In a design for a carriage-body, a shield-shaped side panel meeting at its sides woven cane panels, as shown and described.
4. In a design for a carriage-body, a side panel, *c*, having its center filled in with strips of cane, as shown and described.
5. In a design for a carriage, a body having a rounded front provided with woven cane panels separated by a front panel, *d*, and bordered at top and bottom by an upper and lower rail, *a b*.
6. In a design for a carriage, a body shaped about its upper and lower sides as shown in the cut or illustration, rounded at its ends, provided with woven-cane panels between upper and bottom rails, *a b*, and all surmounted by a plated rail, *g*, to contrast with and trim the upper edge of the body, as shown.

In testimony whereof I have signed my name to this specification in the presence of two subscribing witnesses.

WM. B. WHITNEY.

Witnesses:

HAMILTON MAYO,
ANDREW H. DANFORTH.
